CONDENSER FOR SOIL MOISTURE METER

Joel E. Fletcher, Tucson, Ariz.

Application July 19, 1940, Serial No. 346,373

7 Claims. (Cl. 175—183)

(Granted under the act of March 3, 1883, as amended April 30, 1928; 370 O. G. 757)

This application is made under the act of March 3, 1883, as amended by the act of April 30, 1928, and the invention herein described and claimed, if patented, may be manufactured and used by or for the Government of the United States of America for governmental purposes without the payment to me of any royalty thereon.

This invention relates to a device for electrically measuring the moisture content of soil and is more particularly concerned with the condenser unit thereof which is adapted to be sunk or imbedded in the ground where the moisture determination is to be made.

In the accompanying drawings there are illustrated two general embodiments of my invention. The first embodiment, referred to generally as the plate type, is illustrated in Figures 1, 2, and 3; Figure 1 being a front elevational view, Figure 2 a section along the line 2—2 of Figure 1, and Figure 3 a section along the line 3—3 of Figure 1.

The second embodiment, referred to generally as the cylindrical type, is illustrated in Figures 4, 5, and 6; Figure 4 being a longitudinal section, Figure 5 being a cross section along the line 5—5 of Figure 4, and Figure 6 being a fragmentary elevational view, portions of the dielectric material being broken away to show the helical arrangement of the apertures in the outer cylindrical plate.

Referring with more particularity to Figures 1, 2, and 3, the embodiment illustrated comprises a pair of copper plates 10, which may be of heavy foil, disposed in fixed spaced relation and covered with a coat 11 of lead glass, Lucite, or other suitable material. Between the coated plates 10, a water-absorbent dielectric material 12, such as plaster of Paris, or other suitable material, is disposed. This dielectric material 12 also serves to hold the plates 10 in position. A long hollow pipe 13 is bifurcated at one end to form two forks 14, between which the coated plates 10, together with the dielectric material 12, as a unit, is disposed and secured in place by means of bolt and nut assemblies 15, substantially as shown. Wire leads 16, of shielded microphone cable are connected to the plates 10 at one end; the shield being fastened to one plate and the center lead to the other plate. The other ends of the leads 16 are threaded through the hollow core of the pipe 13 and connected to suitable tip jacks (not shown).

The embodiment illustrated in Figures 4, 5, and 6, comprises a metal base 17 to the bottom of

which is removably secured a spear tip 18. Adjacent the tip 18, the base 17 is recessed to provide a cylindrical core 19 about which there is first disposed a coated cylindrical collar 20 of copper or other suitable material, the coat 21 thereof being preferably of Lucite or lead glass. Another copper cylinder 22 is disposed concentric with the cylinder 20 and likewise covered with a coat 23 of Lucite, lead glass, or other suitable material. The cylinder 22 is larger than the cylinder 20 and the space between their two coatings is filled with plaster of Paris 24, or other suitable water-absorbent dielectric material. The outer cylinder 22 is provided with apertures 25 in helical relation. These apertures are also filled with the dielectric material used between the two cylinders 20 and 22, and on the outside of the cylinder 22 a coating 26 of the same dielectric material is provided. The member 17 is provided with a longitudinal bore 27 through which electrical shielded wire leads 28 are disposed and connected to the cylindrical plates 20 and 22 in the same manner as above described with reference to the first embodiment illustrated in Figures 1, 2, and 3. The upper end 29 of the member 17 is threaded for a removable connection to a suitable pole or rod 30 so that the device can be inserted in the ground at desired depths, as hereinafter explained.

To use either of the two embodiments above-described, a hole is drilled diagonally into the soil to the desired depth with an auger, or other suitable tool, having the same diameter as the condenser unit. The condenser unit is then forced firmly against the bottom and sides of the hole. It is necessary for the exposed portions of the plaster of Paris to press firmly against the soil on the sides of the hole to make a good contact for the passage of the moisture. The sides 40 of the hole should be packed firmly all around and the remainder of the hole filled with soil and packed tight to prevent water from following the pole or rod to the plates. The wire leads from the condenser plates are then connected to a meter for measuring capacity. The capacity of the buried condenser varies with the dielectric constant, which in turn varies with the moisture content in the dielectric material. This moisture content is affected by the moisture of the surrounding soil. The lower the moisture content of the dielectric material the smaller is the value of the dielectric constant and, consequently, the capacity of the condenser is lowered. Thus, the capacity of the condenser becomes a function of the percentage of moisture in the soil.

Having thus described my invention, I claim:

1. A condenser for a soil moisture meter comprising a pair of metal plates disposed in fixed spaced relation, a coating of lead glass about each of the said plates, a plaster of Paris dielectric permanently fixed between said plates; said dielectric being communicable with the soil to be tested.

2. An article of manufacture comprising a rod, a condenser secured at one end of said rod; said condenser comprising a plurality of spaced metal plates, a coating of insulation about each of said plates, a water-absorbent dielectric permanently fixed between said plates, and electrical wire leads attached to said plates for connection to a capacity meter.

3. An article of manufacture comprising a rod having a spear point at one end and a cylindrical recessed portion adjacent said spear point, an insulated metal cylinder disposed about said recessed portion, a layer of water-absorbent dielectric material about said cylinder, an insulated foraminous metal cylinder about said dielectric material, and another layer of water-absorbent material about the exterior of said foraminous cylinder contacting the dielectric material between said cylinder through the perforations of said foraminous cylinder.

4. An article of manufacture as defined by

claim 3 in which the perforations of the foraminous metal cylinder are disposed in helical relation.

5. An article of manufacture comprising a rod having a spear point at one end and a cylindrical recessed portion adjacent said spear point, an insulated metal cylinder disposed about said recessed portion, a layer of plaster of Paris about said cylinder, a perforated and insulated metal cylinder about said layer of plaster of Paris, another layer of plaster of Paris about said perforated cylinder; said layers of plaster of Paris being in contact with each other through the perforations of said perforated cylinder.

10 15 6. A condenser for a soil moisture meter comprising a pair of metal plates disposed in fixed spaced relation, a coating of insulation about each of said plates, a dielectric material permanently fixed between said plates, said dielectric being communicable with soil to be tested and capable of absorbing moisture from said soil.

20 25 7. A device of the character described comprising a condenser having electrode plates, a moisture shield surrounding each of said plates, and a permanent dielectric material between said plates capable of absorbing moisture from adjacent soil, the dielectric constant of said material varying with the quantity of moisture absorbed.
